(57) **CLAIM**

The ornamental design for a down light, as shown and described.

DESCRIPTION

FIG. 1 is a front, bottom, left side perspective view of a down light according to the invention;

FIG. 2 is a front, top, left side view of a down light according to the invention;

FIG. 3 is a front plan view thereof;

FIG. 4 is a left side elevation view thereof;

FIG. 5 is a rear elevation view thereof;

FIG. 6 is a right side elevation view thereof;

FIG. 7 is a top side elevation view thereof; and,

FIG. 8 is a bottom side elevation view thereof.

The broken lines illustrate environmental features and form no part of the claimed design.

1 Claim, 8 Drawing Sheets
